UNITED STATES PATENT OFFICE

167,966

INDOOR TELEVISION ANTENNA

Harold J. Berney, Washington, D. C., assignor to
Aberney Corporation, Bethesda, Md., a corpora-
tion of Maryland

Application April 3, 1952, Serial No. 19,182

Term of patent 14 years

(Cl. D26—14)

To all whom it may concern:

Be it known that I, Harold J. Berney, a citizen of the United States, residing at Washington, in the District of Columbia, have invented a new, original, and ornamental Design for an Indoor Television Antenna, of which the following is a specification, reference being had to the accompanying drawings, forming part thereof, wherein:

Figure 1 is a top plan view of an indoor television antenna showing my new design.

Figure 2 is a front elevational view of the indoor television antenna of Figure 1.

Figure 3 is a side elevational view of the indoor television antenna of Figures 1 and 2.

Figure 4 is a horizontal cross-sectional view taken on the line 4—4 of Figure 3.

The dominant features of my new design reside in those portions shown in full lines.

I claim:

The ornamental design for an indoor television antenna, as shown and described.

HAROLD J. BERNEY.
